WIRE TWISTING DEVICE

Carleton E. Barnett, Cambridge, Mass.

Application May 1, 1937, Serial No. 140,189

3 Claims. (Cl. 140—119)

This invention relates to a wire twisting device or tool especially adapted among other uses to be employed for firmly securing relatively large stoppers or closure members in fluid tight relation to relatively large containers, such as carboys for holding acids and other fluids.

Acid containing carboys are usually made of glass and are provided with a neck having an annular rim about the neck at or near the mouth of the carboy, and said mouth is closed by a stopper or closure member, which is mechanically held in its closed position by a wire retaining member.

The wire retaining member is provided at one end with a loop or ring which is placed on the neck of the carboy or large bottle and the free end of the retaining member is passed over the top of the stopper and down through the loop or ring on the neck of the bottle or carboy.

The loop or ring is of larger diameter than the neck of the carboy and the stopper or closure member is usually provided in its upper surface with a groove or channel for the reception of the retaining wire.

The present invention has for its object to provide a tool or device with which the free end of the wire retaining member and the loop may be twisted together so as to reduce the diameter of the loop or ring and cause it to be brought under the rim on the neck of the bottle or carboy and in firm engagement with the under side of said rim, while at the same time the portion of the wire which is engaged with the stopper is brought firmly in contact therewith and with the circumference of the annular rim on the neck of the carboy, so as to press the stopper into the mouth of the carboy and mechanically hold and lock the stopper against accidental disengagement and thus prevent leakage and waste of the contents of the carboy, especially in transit.

The present invention also has for its object to provide a wire twisting tool with which a maximum number of carboys may be effectively sealed or closed fluid tight in a minimum time and with the least possible effort on the part of the operator.

These and other features of this invention will be hereinafter pointed out in the claims at the end of this specification.

In the accompanying drawing, Fig. 1 is a side elevation of a wire twisting tool embodying this invention, and a sufficient portion of a carboy to illustrate the initial relation of the tool to the retaining wire for the stopper or closure member; Fig. 2 represents the relation of the retaining

wire to the carboy and stopper after the retaining wire has been twisted by the tool, which latter is shown in longitudinal section in one of its operative positions; Fig. 3 is an enlarged detail of a locking device by means of which the members of the twisting tool are normally unlocked in their initial position shown in Fig. 1, but which may be locked together in such position at the will of the operator, and Fig. 4 is an end view of the head on the rotatable member of the tool.

Referring to the drawing, 10 represents the neck of a carboy or other fluid container, 12 the annular rim thereon, 13 the stopper or closure member therefor, and 14 the wire retaining member for the stopper 13. The retaining member 14 is provided at one end with a ring or loop 15 of greater diameter than the rim 12, which may be made by bending one end of a straight piece of wire into the form of a ring which is closed by twisting the bent end of the wire around the straight portion after the manner represented by 16 in Fig. 1.

The loop or ring 15 is of larger diameter than the rim 12 on the neck 10 of the bottle or carboy, so that the ring can easily be placed on the neck 10 below the rim 12, and the straight portion of the wire 14 is then bent over the stopper 13 in a groove or channel 17 in the upper surface of said stopper, and the free end 18 of the wire 14 is passed through the loop or ring 15, as represented in Fig. 1.

The free end of the wire 14 and the loop or ring 15 are then twisted together to diminish the diameter of the loop or ring 15 and cause it to hug the neck of the carboy or other container below the annular rim 12, and at the same time cause the portion of the wire 14 which engages the upper surface of the stopper or closure 13, to be drawn down and exert pressure upon the stopper or closure 13 so as to effectively seal the mouth of the carboy against leakage of the fluid contents of the carboy and to mechanically hold and retain the stopper in its sealed position against accidental displacement, as represented in Fig. 2.

The twisting of the loop or ring 15 and the free end of the wire 14, may be effected in a minimum time by means of the tool herein shown.

The twisting tool herein shown is provided with a rotatable member which comprises a rod or bar 20 normally angular in cross section and preferably square, which is of sufficient length to ensure proper twisting of the loop or ring 15 and the free end of the retaining wire 14.

The rod or bar 20 is provided at one end, which

may be termed its front end, with a twisting finger 22 extended at an angle to the longitudinal axis of the bar 20 and of sufficient length to enable it to be extended up through the loop or ring 15 and engage the portion of the wire 14 above the loop or ring, and remain in engagement with both while the rod or bar 20 is rotated to twist the loop or ring and the free end of the wire 14 into the position and relation to the annular rim 12, shown in Fig. 2.

The twisting finger 22 is attached to a hub 23 having a socket into which a cylindrical projection on the front end of the bar 20 is extended and frictionally or otherwise secured thereto.

The bar 23, between its ends, is twisted so as to provide the bar with helically arranged sides which extend from the hub 23 to near the opposite end of the bar 20 and serve to effect rotation of the bar 20 and its attached finger 22 in the operation of the tool. The rotatable member or bar 20 has cooperating with it a sleeve or hollow member 30, which is provided at its front end with a head 31 having a passage or bore of the same shape in cross section as the helically twisted portion of the bar 20 and through which the said bar is extended.

The head 31 is provided with a passage or bore which is square at its opposite ends, and the corners of one end of the bore or passage are arranged at an angle to the corners of the other end of the bore or passage as represented in Fig. 4, and the side walls of the bore or passage are shaped to correspond with the shape of the twisted side portions of the bar 20. As a result of this construction and arrangement, longitudinal movement of the sleeve 30 on the bar 20 in a straight path, produces rotary movement of the bar 20 and its attached finger 22, and the latter in its rotation twists the loop 15 and the wire 14 together until the loop 15 and wire 14 have been twisted to such extent as to bring the wire retaining member into its operative position shown in Fig. 2. This arrangement enables the wire retaining member to be twisted in a minimum time and serves to enable a maximum number of carboys to be mechanically sealed in a given time, as it is only necessary for the operator to press one hand down on the stopper, insert the finger 22 up through the loop 15 and engage it with the wire 14 as represented in Fig. 1 and then draw the sleeve 30 longitudinally on the bar 20 in the direction of the arrow 34 in Fig. 1, until movement of the sleeve is resisted by the engagement of the retaining wire with the rim 12 of the carboy, as shown in Fig. 2.

Provision is made for locking the sleeve 30 to the bar 20 with the sleeve in its normal position with relation to the bar as shown in Fig. 1, so that both members may be rotated as a unit, when so desired by the operator.

To this end a locking device which is normally inoperative to lock the sleeve 30 to the bar 20 is provided, so that the sleeve 30 may be moved lengthwise on the bar 20 as soon as the twisting finger 22 has been engaged with the loop 15 and wire 14 as shown in Fig. 1. In Fig. 3 one construction of such a locking device is shown, which consists of a plunger or pin 35 slidably mounted in a shell or barrel 36 and provided with a head 37 outside of said barrel. The pin 35 is provided with a collar 38 fast thereon, which is engaged by one end of a spring 39 whose other end engages the bottom wall 40 of the barrel. The spring 39 is normally expanded and moves the pin 35 so that its inner end is substantially flush with the

bottom wall 40 of the barrel and is disengaged from the bar 20. At such time the collar 38 is engaged with the head 41 of the barrel. The head 41 may be fitted into the barrel 36 so as to resist movement by the spring 39, in its expanded position.

The locking device, as above stated, is normally disengaged from the bar 20, but may be engaged therewith by the operator pressing upon the head 37 of the pin 35, so as to cause the inner end of the pin to enter a socket 42 in the bar 20, which socket is located in the bar 20 so as to register with the pin, when the sleeve 30 and bar 20 are in their normal position, shown in Fig. 1. When the sleeve 30 is thus locked to the bar 20, they may be moved by the operator as a unit, which enables the loop or ring 15 to have its rear portion adjacent to the twisted portion 16, drawn by the operator under the rim 12 and into firm engagement with the bottom surface of the said rim. When the loop 15 is thus positioned, the parts of the tool may be turned as a unit as long as the operator presses upon the head 37 of the pin, and the retaining wire 14 may be manually twisted, or as is preferred, as soon as the loop 15 has been drawn under the rim 12, the pressure upon the head 37 of the pin 35 may be removed and the spring 39 allowed to withdraw the pin 35 from the socket 42, thus enabling the sleeve 30 to be drawn longitudinally on the bar 20 and twist the retaining wire into its operative position, shown in Fig. 2.

It will thus be seen, that normally the sleeve 30 is not locked to the bar 20, and as a result, if the loop 15 of the retaining wire is properly positioned under the rim 12 on the neck of the bottle or carboy, the sleeve 30 may be instantly moved longitudinally on the bar 20 by the operator and the retaining wire twisted and brought into its operative position represented in Fig. 2, which enables a maximum number of carboys to be sealed in a minimum time. If the loop 15 of the retaining wire is not properly positioned under the rim 12, it may be so positioned by the operator pressing the thumb of the hand which grasps the sleeve 30 upon the head 37 of the pin 35, so as to lock the sleeve 30 to the bar 20, and then pull upon the sleeve to move the bar 20 locked to it, so as to bring the loop 15 into its proper position with relation to the rim 12 on the neck of the bottle or carboy, after which the operator removes the thumb from the head 37 of the locking device and draws the sleeve 30 lengthwise of the bar 20 to effect the twisting of the loop and the free end of the retaining wire, as above described.

It will thus be observed that the locking of the sleeve 30 to the bar 20 may be effected by the same hand with which the sleeve is moved longitudinally which enables the other hand of the operator to be kept in engagement with the retaining wire and the stopper.

Having thus described the invention, what is claimed is:

1. In a wire twisting tool of the character described, in combination, a rotatable bar provided with a twisting finger and with a helical portion extended lengthwise of said bar, a sleeve mounted on said bar to move lengthwise thereof, and provided with a head having a passage through which the helical portion of said bar is extended and having walls cooperating with the helical portion of said bar to effect rotation of the latter, said bar having a socket in said helical portion and a locking device carried by said sleeve and a coil spring disposed about said pin operative to

normally disengage said pin from said bar, to enable the bar to be rotated by said sleeve with the locking device in its normal or disengaged position.

- 5 2. In a wire twisting tool of the character described, in combination, a rotatable bar provided with a twisting finger and with a helical portion extended lengthwise of said bar, a sleeve mounted on said bar to move lengthwise thereof, and provided with a head having a passage through which the helical portion of said bar is extended and having walls cooperating with the helical portion of said bar to effect rotation of the latter, said bar having a socket in said helical portion, 10 15 and a locking device carried by said sleeve and having a pin cooperating with said socket, said pin being enclosed in a hollow bushing fixed in said sleeve, said hollow bushing having a cylindrical wall and end walls, said end walls being provided with openings through which said pin extends, a collar on said pin disposed within said hollow bushing, a coil spring disposed about the pin between said collar and the inner end wall

of said hollow bushing, said spring being operative to normally disengage said pin from said socket and to dispose said collar against the outer end wall of said hollow bushing, and a head on said pin external to said sleeve and capable of being operated by the hand of the operator which grasps said sleeve and effects engagement of said pin with said bar.

- 5 3. In a wire twisting tool of the character described having, in combination, a handle and a spiral rod rotatable through said handle upon longitudinal movement of the latter, and a locking device including a pin adapted to engage said rod for preventing rotation of the rod with relation to the handle when the rod is in its completely retracted position, and a coil spring disposed about said pin adapted to disengage said pin from said rod, said locking device being normally disengaged and operative to lock said rod to said handle only when manually engaged 10 15 20 by the operator.

CARLETON E. BARNETT.
